UNITED STATES PATENT OFFICE.

ALEXANDER KARSH, OF NEW YORK, N. Y.

DESIGN FOR TRAY OR SIMILAR ARTICLE.

Application filed April 3, 1923. Serial No. 5,682. Term of patent 3½ years.

To all whom it may concern:

Be it known that ALEXANDER KARSH, a citizen of the United States, and resident of the city of New York, in the county of New York and State of New York, has invented a new, original, and ornamental Design for Trays or Similar Articles, of which the following is a specification, reference being had to the accompanying drawing, forming part

thereof, in which the figure shows my new design as applied to a tray.

I claim:

The ornamental design for tray or similar article, as shown.

Signed at New York city, in the county of New York and State of New York, this 2nd day of April, 1923.

ALEXANDER KARSH.
